UNITED STATES PATENT OFFICE

FRANK DITCHFIELD, OF CLEVELAND, OHIO, ASSIGNOR TO THE YOUNGSTOWN STEEL DOOR CO., OF CLEVELAND, OHIO, A CORPORATION OF OHIO

METAL WALL STRUCTURE FOR CARS

Application filed December 28, 1928. Serial No. 328,937.

This invention relates to improvements in metal wall structures for cars.

In the art of metal wall structures for cars and especially box car ends, one of the

5 sources of greatest difficulty, heretofore, has been to obtain a satisfactory connection between the metal sheets and the car frame and more particularly, between the end wall sheets and the end sill. The common practice has been to rivet the lower edges of the sheets to the outer vertical faces of the sills and, because of this arrangement, the securing rivets are placed under tension when

10 stresses are imposed on the end sheets in a direction perpendicular to the sheets from the interior of the car. As obvious, stresses in this direction tend to pull off the rivet heads and tear out the sheets, this being particularly true of box car end walls where

20 very heavy shocks are produced, due to sudden stopping and starting of the cars and the consequent endwise shifting of the lading.

Another serious difficulty encountered is 25 the tendency of the walls, particularly the end walls, to bulge outwardly, either from shifting of the lading or from the more or less fluid-like pressure of certain types of loads, such as grain. To prevent bulging, it

30 has been customary to either apply separate braces to the sheets or corrugate them in any one of numerous ways. The use of separate braces is unsatisfactory because of increased cost of fabrication and material and increase

35 in dead weight of the car. Corrugations, as heretofore employed, have not been entirely satisfactory for several reasons. If the corrugations are extended to the edges of the sheets, great difficulty is experienced in at-

40 taching the sheets to the car frame members and in trimming the corrugated edges of the sheets. On the contrary, if the corrugations are terminated within the edges, weak sec-

45 tions are necessarily left adjacent the lines of securing rivets, which is particularly dis-advantageous in the case of the lower por-tions of box car end walls.

One object of my invention is to provide a 50 metal wall structure for cars wherein is pro-vided great inherent strength against bend-

ing, bulging, weaving or the like and a strong and efficient connection between the metal sheets and the elements of the car framing.

Another object of my invention is to pro-55 vide a metal wall structure for cars, espe-cially adapted as an end wall for box cars, wherein the lower edges of the sheets are connected to the underframe sills by rivets so disposed as to be under shear when 60 the sheets are pressed against outwardly by the lading within the car, whereby to mini-mize possibility of the rivet heads or sheets tearing out.

A further object is to provide an integrally 65 corrugated wall structure and more partic-ularly, a car end wall, wherein the corru-gations may be made as deep as desired, to provide the necessary strength against bend-ing or bulging and at the same time extend-ing to the line of the connection of the car 70 frame elements, the termini of the corru-gations being so formed that the sheets can be readily drawn by dies without tearing or 75 weakening of the sheets.

Among other objects of the invention are to so form the wall sheets as to avoid ex-terior pockets that might otherwise collect 80 water, snow, etc., and promote corrosion; to provide flat marginal flanges along the edges 85 of the sheet in order that the same may be properly trimmed and trued; to provide con-nections along the top edges of the sheets with the side or end plates, such that the webs of the usual Z-bar types of plates are 90 directly utilized in resisting outward thrusts on the wall; to so fabricate the wall sheets that variations in sizes thereof may be read-ily accommodated in forming the same by a simple interchange of a sectional die; and 95 to otherwise improve the efficiency and econ-omies of structures of the type indicated.

In the drawings forming a part of this 95 specification, Figure 1 is an elevational view of an end of a box car showing my improve-ments applied thereto, parts being broken away in order to better accommodate the view on the sheet. Figures 2 and 3 are en-larged vertical sectional views correspond-ing to the section lines 2-2 and 3-3, re-100

spectively, of Figure 1. And Figures 4 and 5 are horizontal sectional views corresponding respectively to the section lines 4-4 and 5-5 of Figure 3.

5. In said drawings, 10-10 indicate center sills of a car underframe of the usual construction; 11-11 channel side sills; 12 a T-bar end sill; 13 a Z-end plate, and 14 the ends of the roof sheets.

10 The end sill 12 is formed with an inwardly extending flange 112, an outwardly extending flange 212 and an upstanding centrally disposed web 312, it being understood that the flanges 112 and 212 are riveted to
15 the center and side sills to form a rigid connection with the underframe sills. The end plate 13, shown in the form of a pressing, is formed with an upstanding vertical flange 113, a horizontally outwardly extending web
20 section 213 and an outer downturned flange 313.

In carrying out my invention, when my improvements are applied to an end wall of a box car, I preferably employ three panels 25 A, B and C, the panels A and C being at the ends and complementary and the panel B being at the center. The panels have overlapped flanges along their meeting edges, which are riveted with a vertical line of 30 rivets, as indicated at 15-15.

The metal wall, preferably comprised of the three panels, is provided with a plurality of vertically extending corrugations 16, which are preferably inwardly offset from the original plane of the sheet. The valleys of these corrugations are indicated at 116 and the outwardly diverging side walls thereof are indicated at 216-216, so that there are provided, between each pair of corrugations, what may be termed an outer or crest section 17, the latter being in the original plane of the sheet. The corrugations 16 may be made of any desired depth, to provide the necessary bracing strength against bending or bulging of the end walls, those shown in the drawings being drawn to a scale indicating a depth of approximately $3\frac{1}{2}$ ".

For the greater part of their length, the 50 valley sections 116 of the corrugations are preferably in the same plane as the web 312 of the end sill, as shown best in Figures 2 and 3. At their bottoms, said valley sections 116 are slightly outwardly offset, as indicated at 18, so as to overlie the outer face of the end sill web 312 and provide a flat surface bearing thereagainst and by which the end sheets are directly riveted to the end sill, as by the rivets 19. Below the line of 55 rivets 19, the valley sections 116 are sloped downwardly and outwardly, as indicated at 20 and then merge into a flat securing flange section 21, the latter being of sufficient width within each corrugation as to admit the use 60 of two securing rivets 22—22 for each cor- 65

rugation to the securing flange 212 of the end sill, as best shown in Figures 2 and 4. In this connection, it will be observed that the rivets 22 have their axes extended vertically and consequently when an outward pressure is applied to the end wall, said pressure will be transmitted through the sheets in such manner as to place the rivets 22 under direct shear, thus providing an extremely strong, rigid and permanent connection between the end wall and the end sill and one which is materially stronger than those heretofore used.

Due to the relatively great depth of the corrugations which has been found necessary, to resist bending or bulging of the end walls, and because of the desirability of extending these corrugations completely up to the line of attachment with the horizontal frame elements of the car, provision must be made to avoid undue stretching or tearing of the sheets during the die-forming operation, which might otherwise occur in attempting to obtain the horizontal overlapping with the end sill to accommodate the vertical rivets which are under shear. To avoid any undue stretching of the metal, I therefore reduce the depth of what may be termed the oppositely facing corrugations 17 by necking-in or inclining inwardly the lower portions of the corrugations 17, as indicated at 117 best in Figure 3. The inwardly inclining lower section 117 is extended down to the securing flange 212 where it is then curved outwardly, as indicated at 217 and merged as indicated at 317 with the securing flange section 21, previously mentioned. In this manner, as best indicated in Figure 5, the relative depths of the alternate inwardly and outwardly facing corrugations is reduced approximately one-half, so that danger of tearing or unduly stressing the metal during the die-forming operation is avoided while at the same time retaining the effective strength of the corrugations completely down to the end sill and thus avoiding a weak section of the wall structure at any point.

As shown in Figures 2 and 3, the securing flange 21 is finally extended vertically downward, as indicated at 121, to form an overhanging marginal flange. This marginal flange 121 not only serves to weather protect the joint between the wall sheets and the sill but also permits trimming of the edge of the sheet and truing thereof between ordinary dies and trimming shears, that is, the marginal flange section 121 is disposed parallel to the general plane of the sheets and hence may be trimmed without the aid of special machinery, which would otherwise be necessary if a corrugated edge were to be trimmed or if the edge to be cut were narrow and in a plane perpendicular to the general plane of the sheet.

At the top of the wall structure, a general-

ly similar arrangement is employed, except that in this instance the valley sections 116 are outwardly and upwardly sloped, as indicated at 316, thus reducing the effective depth 5 of the alternating inwardly and outwardly facing corrugations along the upper edge. The outer or crest sections 17 of the corrugations are secured to the depending flange 313 of the end plate by a horizontally extending 10 series of rivets 24. At the upper termini of the corrugations, the sheet is extended inwardly and slightly upwardly, as indicated at 25 for a distance approximately equalling the width of the web 213 of the end plate and 15 thence is extended vertically to provide an upper marginal flange 26 overlying the inner face of the flange 113 of the end plate and to which it is secured by another horizontally extending series of rivets 27. With this construction, 20 it will be observed that the web 213 of the end plate is directly utilized in its most effective manner, to resist any tendency of the end wall to be bent or bulged outwardly, since the end sheet is connected to the 25 end plate by the two series of rivets 24 and 27. Further, it will be noted that a continuous tight joint is obtained throughout the full width of the end wall between the end plate flange 13 and end wall sheet flange 26, this 30 joint being effectively weather-protected by the overhanging flange 313 which acts as a hood to prevent rain, snow or the like being driven up into the joint.

Referring to Figures 4 and 5, it will be 35 seen that the adjacent edges of the panels A, B and C are overlapped as indicated at 28—28 and riveted along the overlapped joints. Partly for the purpose of obtaining shallowness of the corrugations at the overlapped 40 joints, in order to prevent undue stretching of the metal at the end corrugations, and partly to maintain the line of rivets securing the overlapped portions, the edges of the panel sheets are partially necked in as indicated at 45 29, so as to leave a narrow corrugation of full depth and a wider portion of only half depth. The outer side edges of the panels A and B are provided with plain flanges 30—30 at 50 right angles to the main plane of the end wall and which are adapted to overlie and be secured to the corner posts of the car superstructure.

In order to provide for the usual interior 55 wood sheathing, vertically extending nailing strips 31—31 may be disposed in those inwardly facing corrugations which are defined at the overlapped secured edges of the respective pairs of panels, as clearly shown in Figures 4 and 5.

In fabricating the panels, variations in 60 height may be readily and economically accommodated by using sectional dies whereupon those die sections which form the upper and lower portions of the panels always remain 65 the same and the intermediate die sections

which form the central plain portions of the corrugations are made interchangeable as to width. Further, variations in over-all width of the end wall structure may be accommodated, within reasonable limits, by varying the width of the plane flat edge portions 32, that is, by forming the marginal flanges 30 closer to or farther from the outermost corrugation 16.

From the preceding description, it will be 75 seen that I have provided a metal wall structure for cars and more particularly, end walls for box cars which may be economically manufactured; which provides great inherent strength against outward bending or bulging; which avoids any weak sections, particularly at the line of attachment to the horizontal frame elements of the car; which provides for variations in dimensions without increase in cost of manufacture, and which 80 avoids excessive stretching of the metal at any point.

Attention is also called to the fact that the inwardly extending flanges of the T-sills provide a shelf for the edges of the floor boards 90 and that the webs of the T-sills are extended vertically sufficiently to prevent any water or moisture from dripping over to the outer side, which might collect within the wall sheets and induce corrosion. Further, by providing vertically extending corrugations in the wall sheets, I am enabled to use vertical nailing strips which in turn permit the use of horizontally disposed lining boards, a much 95 more efficient construction than where the lining boards are extended vertically, as generally necessary in the event of horizontal corrugations being used to reinforce the wall sheets.

Particular attention is directed to the efficiency of the vertically extending corrugations and attaching arrangement at the bottom. As is well known, the maximum pressure outwardly against the car end wall is approximately 30" above the floor line, which 100 distance is appreciably less than half the width of the car end. Where horizontal corrugations are employed in an end wall, the length of the arm of the bending moment from the corner post, is 4' or more and hence, 105 at a point 30" above the floor line, a relatively weak section obtains, since this portion of the end wall may be bent outwardly comparatively easily. By employing vertical corrugations, the arm of the bending moment 110 is only 30" above the floor line and hence, for a given weight of metal, a stronger construction may be obtained, or, stated conversely, 115 the same strength may be obtained with a lighter gauge of sheet metal, employing vertical corrugations, than where horizontal corrugations are employed.

I claim:

1. In a metal wall structure for cars, the combination with a metal rolled frame ele- 130

ment having an attaching section disposed perpendicular to the general plane of the wall; and a wall-forming sheet having strengthening indentations therein extended to said flange and provided also with an integral flange section extending across the ends of said indentations engaging and secured to said attaching flange of the frame element.

2. In a metal wall structure for cars, the combination with a metal rolled frame element having a horizontally disposed securing flange; of a wall-forming sheet having vertically disposed corrugations therein extended to said securing flange and provided with an integral flange at the termini of said corrugations engaging and secured to said horizontal flange.

3. In a metal wall structure for cars, the combination with a metal rolled frame element having an attaching flange disposed perpendicular to the general plane of the wall; of a wall-forming sheet having corrugations therein disposed perpendicular to said frame element and extended to the attaching flange thereof and provided also with an integral securing section at the termini of said corrugations and secured to said attaching flange of the frame element.

4. In a metal wall structure, the combination with a T-bar sill having a horizontal flange; of a wall-forming metal sheet having vertically disposed corrugations therein extended to said flange, said sheet being provided with an integral securing flange at the termini of said corrugations extending thereacross, said securing flange being riveted to the sill flange.

5. In an end wall structure for cars, the combination with an angular rolled end sill having a horizontal flange; of an end wall-forming metal sheet having vertically disposed corrugations therein extended to said flange and provided also with an integral securing flange extending across the ends of said corrugations, said securing flange overlying and being attached to said sill flange.

6. In a metal wall structure for cars, the combination with a T-bar frame element having its flanges disposed horizontally and the web vertically; of a wall-forming metal sheet having corrugations therein arranged perpendicular to said T-bar and extended thereto, the valleys of said corrugations being riveted to the T-bar web, said sheet having also a securing flange at the ends of said corrugations adjacent the T-bar, said flange being riveted to one of the T-bar flanges.

7. In a metal end wall structure for cars, the combination with a T-bar end sill having its web extending vertically upward; of an end wall-forming metal sheet having vertically arranged corrugations therein, the latter being extended downwardly to a flange of said sill, said sheet having an integral flange at the lower ends of said corrugations

overlying and secured to one of the flanges of the T-bar.

8. In a metal wall structure for cars, the combination with a sill having a horizontally disposed attaching section; of a wall-forming metal sheet having vertically disposed corrugations extended to said attaching section of the sill, said corrugations being of shallowed depth adjacent said sill and said sheet having an integral securing flange aligned with said shallowed ends of the corrugations, said flange being secured to the attaching section of the sill.

9. In a metal end wall structure for cars, the combination with an end sill having a horizontally disposed attaching section, of an end wall sheet having vertically disposed corrugations therein extended downwardly to said attaching section of the end sill, said corrugations being of decreased depth at their lower ends and the sheet being provided with an integral horizontally disposed securing flange, said flange being riveted to the attaching section of the end sill.

10. In a metal end wall structure for cars, the combination with a T-bar end sill having its web extended vertically upward; of an end wall sheet having vertically disposed corrugations therein extended downwardly to one of the flanges of the T-bar sill, said corrugations being of gradually reduced depth at their lower ends, said sheet having an integral securing flange at the bottom alined with said corrugations and overlying one of the T-bar flanges and secured to the latter.

11. As an article of manufacture, a metal wall-forming sheet for cars, said sheet having a plurality of parallelly arranged corrugations therein and a securing flange disposed perpendicularly to the general plane of the sheet at one set of ends of the corrugations, the latter extending to said flange and being of gradually reduced depth adjacent said flange, whereby to avoid excessive stress of the metal when the corrugations and flange are formed therein.

12. As an article of manufacture, a metal wall-forming sheet for cars, said sheet having a plurality of parallelly arranged corrugations therein and a securing flange disposed perpendicularly to the general plane of the sheet at one set of ends of the corrugations, the latter extending to said flange and being of gradually reduced depth adjacent said flange, whereby to avoid excessive stress of the metal when the corrugations and flange are formed therein, said flange having an extension margin disposed perpendicular to the securing flange and in the general plane of the sheet.

13. In a metal wall structure for cars, the combination with a Z-shaped frame element having the web section thereof extending perpendicular to the general plane of the wall; of a wall-forming metal sheet, said

sheet having strengthening indentations, alined with said web and provided with an end flange section having a terminal marginal flange, the latter being secured to one flange of the Z-bar element and other portions of the sheet being secured to the other flange of the Z-bar element.

14. In a metal wall structure for cars, the combination with a Z-shaped frame element having the web thereof arranged perpendicular to the general plane of the wall; of a wall-forming metal sheet having corrugations therein arranged perpendicular to said frame element and extending thereto, said sheet having a flange at the end adjacent said element, said flange having a portion overlapping and secured to one of the flanges of the Z-shaped element, the valleys of some of the corrugations being secured to the other flange of said element.

15. In a metal end wall structure for cars, the combination with a Z-bar end plate; of an end wall metal sheet having vertically disposed corrugations therein extending to said plate, said sheet having an upper edge flange provided with a marginal portion overlying and riveted to one of the flanges of said Z-plate, the valleys of the corrugations being riveted to the other flange of the Z-plate.

16. In a metal wall structure for cars, the combination with a sill having a horizontally disposed attaching flange; of a plate of Z-form; and a wall-forming metal sheet extending between and secured to said sill and plate, said sheet having vertically disposed corrugations therein, extending to the sill and plate, said sheet having an integral securing flange at the lower terminii of the corrugations riveted to the attaching flange of the sill, said sheet having an integral flange along its upper edge, a section of which overlies and is riveted to one flange of the Z-bar plate, the valleys of one set of corrugations being riveted to the other flange of said Z-bar.

17. In a metal end wall structure for cars, the combination with a T-bar end sill; of a Z-bar end plate; and an end wall sheet, the latter having vertically disposed corrugations extending to the sill and end plate, said sheet having integrally formed securing flanges along the top and bottom edges, the lower securing flange overlying and being riveted to one of the flanges of the T-end sill, the flange at the top of the sheet having a marginal section overlying and riveted to the upstanding flange of the Z-plate, said corrugations being of reduced depth at their upper and lower ends.

18. In a metal wall structure for cars, the combination with a horizontally disposed T-bar frame element having the web thereof arranged parallel to the plane of the wall and one of the flanges extended horizontally out-

wardly therefrom; of a wall sheet having corrugations therein alined with said outwardly extended flange, said corrugations extending beyond the free edge of the web of the T-bar; and means for securing the sheet to the outwardly extended flange of the T-bar.

19. In a metal wall structure for cars, the combination with a T-bar sill having the web extended vertically upward and one of the flanges extended horizontally outward; of a wall-forming metal sheet having corrugations therein and extended downwardly below the top edge of said web in line with the outwardly extended flange; and means for attaching the lower edge of the sheet to said outwardly extended flange.

20. In a metal wall structure for cars, the combination with a horizontally disposed T-bar frame element having the web thereof extended parallel to the plane of the wall and one of the flanges extended outwardly; of a metal wall-forming sheet having portions thereof secured to said web and said outwardly extended flange.

21. In a metal wall structure for cars, the combination with a T-bar sill having its web extended vertically upward and one of its flanges extended horizontally outward; and a metal wall-forming sheet secured both to said web and to said outwardly extended flange along the lower edge of the sheet.

22. In a metal wall structure for cars, the combination with a T-bar sill having its web extended vertically upward and one flange horizontally outward; of a metal wall-forming sheet secured along its lower edge to said outwardly extended flange, said sheet having a marginal flange along its bottom edge depending below and weather-protecting said horizontal flange of the T-bar sill.

23. In a metal wall structure for cars, the combination with a T-bar sill having its web extending vertically upward and one of its flanges extending outwardly; of a metal wall-forming sheet having vertically disposed corrugations therein extending down to said flange, said sheet being secured to said flange and provided with an integral marginal flange depending below said T-bar flange.

In witness that I claim the foregoing I have hereunto subscribed my name this 17th day of December, 1928.

FRANK DITCHFIELD.
